W EARL SNYDER, OF CINCINNATI, OHIO, ASSIGNOR TO THE EDNA BRASS MANUFACTURING COMPANY, OF CINCINNATI, OHIO, A CORPORATION OF OHIO

FORCE FEED LUBRICATOR

Application filed March 23, 1931. Serial No. 524,523.

This invention relates to improvements in force feed lubricators, power driven and particularly applicable for locomotive engine service for a centralized distribution lubricating system, automatically delivering under pressure metered charges of oil in the correct amount to various and numerous bearings while the locomotive or machinery is running, eliminating hand lubrication and 10 service and assures perfect lubrication for all points.

The improvement primarily is directed to the forcer or pumping units of the lubricator of the type as shown in a pending application to Elmer O. Corey, filed Aug. 31, 1928, Serial No. 303,204. The lubricator having a forcer or pumping unit for each outlet or feed therefrom.

An object of the invention is to improve 20 the structure of the pumping unit to increase its durability and efficiency and to render it readily removable from the reservoir of the lubricator to which it is attached, for making repairs or regrinding the valve parts, 25 as a reciprocating plunger and valve, confined within a cylinder and to be removed from an exterior of the lubricator by detaching the cylinder and without disturbing or interfering with the driving or actuating 30 parts housed and supported within the reservoir of the lubricator.

Other objects and features relate to details 35 of construction all of which will be more fully set forth in the following description of the accompanying drawing, forming a part of this specification, in which:—

Figure 1 is a central vertical section through the lubricator reservoir and one of the forcer or pumping units containing my 40 improvements.

Figure 2 is an enlarged section through a pumping unit, taken on line 2—2, Figure 1, showing the plunger at the end of its down stroke.

Figure 3 is a section on line 3—3, Figure 2.

Referring to the drawing, 1 indicates a lubricator reservoir of a determined capacity for the number of feed outlets or pumping units provided. The body is approximately of rectangular form in horizontal cross section and interiorly divided by a horizontal septum or web 2, providing a fill chamber 3 immediately above the reservoir portion 4, communicating with the reservoir through one or more openings 5 in the web 2 covered 50 by a screen or strainer 6. A lid or cover 7 provides a closure for the fill chamber hingedly connected to the rear wall of the body or reservoir and clamped in its closed position by clamp pins 8, hingedly engaged, each 60 between a pair of lugs extending from the forward side or wall of the reservoir and engaged between lugs 10, extending from the forward side of the cover and locked by a lock nut 11, screwthreaded upon the clamp 65 pin 8.

An eccentric shaft 12 extends longitudinally through the interior of the reservoir and journaled in bearings carried by the reservoir casing with one end of the shaft, exteriorly of the reservoir, connected to transmission mechanism, not shown, for intermittently rotating the shaft. A second shaft or rod 13 is supported within the reservoir and extends parallel and in rear of the eccentric 70 shaft. This rod pivotally supports a yoke lever or pitman 14, one for each forcer or pumping unit of the lubricator and has its forward end bifurcated to yoke or straddle the eccentric shaft 12 so as to be actuated 75 thereby with each rotation of the shaft. One limb or arm 15 of the pitman extends forwardly beyond the eccentric shaft and has a ball end engaging upon the upper end of a plunger valve 16 of the pumping unit so 80 that the valve is positively depressed with each downward swing or stroke of the pitman.

The pumping unit comprises a cylinder 17 having a gland or flange 18 extending from 85

its periphery for securing the cylinder to the base of the reservoir with an upper portion of the cylinder extended into the reservoir, through a bore in the base of the reservoir. 5 The upper portion of the cylinder within the reservoir is provided with a plurality of openings 19 therethrough for communication with the reservoir, and the openings protected by a screen band 20 recessed within the 10 periphery of the cylinder. The screen prevents sediment in the lubricant from entering the cylinder which may interfere with the efficiency of the pump. The upper portion of the cylinder is counterbored to provide a 15 shoulder for the flanged head of a cylindrical bushing 21 screwthreaded concentrically into the lower portion of the cylinder.

A tubular plunger 22 has its lower end slidably, concentrically engaged into the bushing 21 and its upper end provided with a head 23 guidingly slidable within the upper end of the cylinder and socketed into the lower end of a yoke 24, also slidably guided within the upper open end of the cylinder and provides 25 a movable guide for the head of the plunger valve 16. The yoke 24 straddles the ball end of the pitman arm 15 and its upper end has a stem 25 connected therewith and vertically slidably engaged into a bore of a guide stud 30 vertically within the fill chamber of the reservoir and screwthreaded into the web 2. The guide stud is provided with a set screw 27 forming an adjustable stop for the stem 25 of the yoke to limit and regulate the upper 35 stroke of the tubular plunger 22.

The upper end of the tubular plunger 22 is counterbored to provide a shoulder and seat for the plunger valve 16 to close the bore of the plunger 22 in a down or feeding stroke of the parts for forcibly discharging the oil from the cylinder, and a second shoulder for seating one end of a spring 28 interposed between the head of the plunger and head of the valve 16. The plunger 22 immediately above the valve seat is laterally bored to provide openings 29, as inlets from the cylinder chamber 30 into the bore of the plunger 22 when the valve 16 is unseated.

A spring 31 for automatically retracting the plunger 22, with the retreat stroke of the valve 16 is interposed within the cylinder chamber 30, between the head of the plunger and flange of the bushing 21.

The lower end of the cylinder 17 is sealed by a hollow screw cap 32, housing a ball check valve 33, screwthreaded into the lower end of the bushing 21, with its valve closing to the bore of the plunger. The lower end of the cylinder is also provided with an L conduit extension 34 to which the pipe connections for conducting the lubricant to the bearing, are made. The connections preferably comprise a union coupling 35, a second check valve 36 and a second union coupling 37 to which the pipe line is secured.

With each up stroke of the pitman 14, the valve 16 and plunger 22 with the yoke 24 coordinately retreat automatically under the tension of the respective springs 28, 31, the valve in each instance moving a full stroke corresponding to the upper stroke of the pitman, while the plunger moves up only for the regulated amount and variable to the movement of the valve, allowing the valve to unseat for the admission of oil into the bore of the plunger and cylinder space below the plunger. The cylinder chamber 30 as well as the ports 29 of the plunger are always open to the supply of the reservoir so that oil is taken into the bore of the plunger as soon as the valve is unseated. As soon as the pitman commences on its down stroke it will move the valve down, closing the bore of the plunger, and carry the plunger therewith for oil discharge from the cylinder and through the check valves and distributing pipe.

The plunger movement is regulated by adjusting the set screw 27, which governs plunger displacement and thereby various metered quantities of oil can be discharged to meet the different requirements.

The adjustment and regulation can be made at will and while the lubricator is in operation by merely resetting the set screw 27. The set screw can be adjusted to an extreme position to allow an excess of plunger movement avoiding valve unseating so that no lubricant will be admitted into the bore of the plunger and thus serve as a means for cutting off the supply to a given line without disturbing the operation of the other pumping units of a lubricator.

The pumping unit can be readily removed from the reservoir for repairs and without removing or disturbing the yoke, by unbolted the cylinder, the cylinder, plunger and valve can be slipped out from the reservoir casing.

Having described my invention, I claim:

In a lubricator, a reservoir body, a pump unit fixed to the base of the reservoir body providing a pressure feed outlet for the lubricator and comprising a cylinder having an upper end engaged through the base of and into the reservoir of the body, a tubular plunger engaged into and guidingly sustained within the cylinder, the upper end of the plunger counterbored to provide a valve seat, said plunger having lateral ports therethrough immediately above the valve seat for the admission of fluid from the reservoir through lateral ports in the cylinder into the bore of the plunger when open at the valve seat and to be forcibly discharged therefrom in a power stroke of the plunger when the bore is closed at the seat, a spring for automatically retreating said plunger, a plunger valve guidingly sustained in the upper end of the bore of the plunger cooperating with said seat to close the plunger bore in a power

stroke of the valve, a spring for automatically retracting said valve, power driven means for positively depressing said valve and in turn said plunger upon the seating of the valve and movable means guidingly sustained in said cylinder and providing an adjustable abutment for the plunger and relative variable retreat of said plunger and valve and to guidingly sustain the valve.

10 In witness whereof, I hereunto subscribe my name.

W EARL SNYDER.
